(57) **CLAIM**

I claim the ornamental design for a intubation stylet or airway exchange catheter or airway introducer, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of an intubation stylet or airway exchange catheter or airway introducer having zone indicators according to an embodiment.

FIG. 2 is a front view of the stylet or airway exchange catheter or airway introducer of FIG. 1.

FIG. 3 is a rear view of the stylet or airway exchange catheter or airway introducer of FIG. 1.

FIG. 4 is a left side view of the stylet or airway exchange catheter or airway introducer of FIG. 1.

FIG. 5 is a right side view of the stylet or airway exchange catheter or airway introducer of FIG. 1.

FIG. 6 is a perspective view of an intubation stylet or airway exchange catheter or airway introducer having colored zone indicators according to an embodiment.

FIG. 7 is a front view of the stylet or airway exchange catheter or airway introducer of FIG. 6.

FIG. 8 is a rear view of the stylet or airway exchange catheter or airway introducer of FIG. 6.

FIG. 9 is a left side view of the stylet or airway exchange catheter or airway introducer FIG. 6.

FIG. 10 is a right side view of the stylet or airway exchange catheter or airway introducer of FIG. 6.

FIG. 11 is a perspective view of an intubation stylet or airway exchange catheter or airway introducer having colored zone indicators according to an embodiment.

FIG. 12 is a front view of the stylet or airway exchange catheter or airway introducer of FIG. 11.

FIG. 13 is a rear view of the stylet or airway exchange catheter or airway introducer of FIG. 11.

FIG. 14 is a left side view of the stylet or airway exchange catheter or airway introducer of FIG. 11; and,

(Continued)

FIG. 15 is a right side view of the stylet or airway exchange catheter or airway introducer of FIG. 11.

The portions of the stylet shown in broken lines are included for the purpose of illustrating environment and form no part of the claimed design.
